Inventor:

Joseph Daving,
By his Attorney,

Geo. F. Knott

UNITED STATES PATENT OFFICE.

JOSEPH DAVING, OF NEW YORK, N. Y.

WATCHCASE.

Application filed June 2, 1921. Serial No. 474,356.

To all whom it may concern:

Be it known that I, JOSEPH DAVING, a citizen of the United States, and a resident of the borough and county of Bronx, city and State of New York, have invented certain new and useful Improvements in Watch-cases, of which the following is a specification.

While adaptable for use in conjunction with watch cases generally, my improvements are designed more especially for incorporation in a case for the work frame of a wrist or convertible (pendent) watch,—my object being to attain simplicity and economy of form, and manufacturing manipulation, combined with strength and efficiency of structure; and the invention consisting in the specific construction, combination, and arrangement of parts and devices herein described and claimed,—a distinctive feature being the one-piece medial member of my improved case formed with protrusive end loops for attachment to a wrist band, suspender, or the like, as hereinafter set forth.

25 In the accompanying drawings, Fig. 1, represents an elevation of either side of my new watch-works-frame holder or casing;

30 Fig. 2, is a central longitudinal section taken upon plane of line 2—2, Fig. 1;

35 Fig. 3, is an elevation of the inner side of the back plate of the casing;

Fig. 4, is a front elevation of the front or bezel member of the casing;

40 Fig. 5, is a representation in elevation of either side of the medial or basic loop section of my watch-works-frame holder;

Fig. 6, is a view of the inner side of either one of the cheek plates before attachment to the basic loop section;

45 Fig. 7, is a view of the outer side of the cheek plate shown in Fig. 6;

Fig. 8, is a view similar to Fig. 5, showing a modification in the exterior loop formation;

Fig. 9, is a perspective view of the parts assembled, with the back plate and bezel plate hinged to the works-frame casing.

What I herein designate for convenience 50 of description as the medial or basic loop section or plate B, of my improved structure of watch-works-frame casing is shown in elevation in Fig. 5; and Fig. 2, incidentally shows a section thereof, said plate B, being formed with laterally protrusive loops b, b, at opposite sides or ends thereof which pro-

trude from the finished casing, and constitute means whereby the casing, in a unitary sense, and including the watch works container frame mounted therein (indicated in dotted lines in Figs. 1 and 9) may be attached directly to a wrist band as indicated in dotted lines in Fig. 9; or to a suspender for use as a bosom pendent by means of a snap hook coupling as indicated by dotted lines in Fig. 8, in which latter case protrusive plural loops b', b', may be provided on each side of the casing, constituting the equivalent of the twin loops provided for this purpose in my concurrent application Serial No. 471,552, filed May 23, 1921.

The medial loop section B, is of course formed with the central opening b^x, for the accommodation of the watch works frame; and the inner edges of this works recess b^x, are preferably rabbeted, as at b², b², on either or both sides, to receive the inturned edges c, c, of the cheek plates C, C, although I do not confine myself to this form of joint, since the rabbet-grooves b², b², may be omitted and the inturned edges c, c, of the cheek plates attached directly to the flat surfaces of the said medial loop plate B, if preferred, and without departing from the spirit and intent of my invention in this respect. In either case, the cheek pieces C, C, are soldered or brazed to the medial plate B, by means well known in the art, so as to become an integral rigid part of the unitary structure of watch-works-frame holder thus constituted, it being understood of course that said cheek pieces C, C, are formed with coincidental central openings c', c', to accommodate the watch-works-frame, which latter is secured in the casing in any desired or usual manner known in the art.

The back plate d, and the bezel plate or frame e, are hinged to the medial plate B, in the usual manner as indicated in Fig. 9, of the drawings, and function as heretofore to protect the watch-works-frame and its casing.

By my formation and arrangement of parts I attain simplicity and strength of structure, especially in so far as the attachment loops b, b, or b', b', are concerned, because the said loops are in one integral piece with the medial basic section plate B, as shown more particularly in Fig. 5, of the drawings, thus not only obviating the labor involved of soldering such loops, but at the same time eliminating the danger of rup-

ture or detachment thereof when separately formed and soldered, as heretofore, to the casing.

It is to be understood that the particular shape of casing shown in the accompanying drawings is incidental only, and that the essential features of my invention may be incorporated in and with other desired or suitable configuration of casing. Furthermore, the drawings show the parts on a larger scale than those usually employed in actual practice.

Obviously the simplicity of the component parts of my casing adapt them for formation by dies, so that the cost of production is reduced to a minimum, while effecting a structure of maximum strength.

What I claim as my invention and desire to secure by Letters Patent is,

- 20 1. A watch case of the character designated, comprising a centrally apertured medial basic section plate formed with protrusive attachment loops, and centrally apertured cheek plates incorporated integrally with said medial basic plate, for the purpose set forth.
- 25 2. A watch case of the character designated, comprising a centrally apertured medial basic section plate formed with protrusive attachment loops, centrally apertured cheek plates incorporated integrally with said medial basic plate, and back and bezel plates hinged thereto, for the purpose described.
- 30 3. A watch case of the character designated, comprising a centrally apertured medial basic section plate formed with protrusive attachment loops and with a cen-

tral aperture having rabbeted inner edges, and centrally apertured cheek plates formed with inturned edges fitting the rabbeted edges of the central aperture of said medial basic plate, and incorporated integrally therewith, for the purpose described.

4. A watch case of the character designated, comprising a centrally apertured medial basic section plate formed with protrusive attachment loops and with a central aperture having rabbeted inner edges, and centrally apertured cheek plates formed with inturned edges fitting the rabbeted edges of the central aperture of said medial basic plate, and incorporated integrally therewith, together with back and bezel plates hinged thereto, for the purpose described.

5. A wrist watch case comprising a chambered center element provided with means for attaching supports at the ends thereof and a pair of covers separately hinged to said element on opposite sides thereof.

6. A watch case comprising a chambered center element containing a central opening and provided with a substantially peripheral flange, and a pair of covers hinged to said element on opposite sides thereof.

7. A watch case comprising a chambered center element provided with a flange extending along a median line and means for attaching supports at the ends thereof, and a pair of covers hinged to said element on opposite sides thereof.

JOSEPH DAVING.
